* cited by examiner

(**) Term: **14 Years**

Primary Examiner — John Windmuller

(21) Appl. No.: **29/413,918**

(74) *Attorney, Agent, or Firm* — McHale & Slavin, P.A.

(22) Filed: **Feb. 22, 2012**

(57) **CLAIM**

(51) **LOC (10) Cl. 08-08**

The ornamental design for an accessory for air drying golf
gloves, as shown and described.

(52) **U.S. Cl.**

DESCRIPTION

USPC **D8/395**; D32/63; D32/64

FIG. 1 is a perspective view of the accessory for air drying
gloves of the instant invention;

(58) **Field of Classification Search**

FIG. 2 is a right side view thereof;

USPC D8/394-396, 72, 367, 373; D19/56, 65,
D19/86; 24/67.3; D32/60-64; D28/40

FIG. 3 is a left side view thereof;

See application file for complete search history.

FIG. 4 is a top view;

(56) **References Cited**

FIG. 5 is a bottom view;
